TELESCOPE SIGHT MOUNT FOR
SHOULDER ARMS

Leslie E. Whittemore, Dorchester, Mass.

Application June 20, 1945, Serial No. 600,479

3 Claims. (Cl. 42—1)

1

This invention relates to a telescope sight mount for breech loading shoulder arms of the top ejection type, and one object of the invention is to provide a novel mounting for the telescope sight which is so constructed that when the telescope sight is in operative position, it is situated directly over the barrel and the receiver but when the bolt is retracted preparatory to feeding a fresh cartridge into the firing chamber, the telescope sight is moved positively laterally to one side of the top opening through which the empty shell is ejected, the mounting being also constructed so that when the bolt is moved forwardly to feed a cartridge into the firing chamber, the telescope sight will be automatically restored positively to its operative position.

Other objects of the invention are to provide various improvements in telescope sight mountings as will be hereinafter set forth.

In the drawings herein I have illustrated a selected embodiment of my invention.

Fig. 1 is a fragmentary view of a breech loading fire arm equipped with my improved telescope sight mounting, said figure showing the bolt in its forward, or closed position and the telescope sight in its operative position.

Fig. 2 is a view similar to Fig. 1 but showing the bolt retracted and the telescope sight in its inoperative position.

Fig. 3 is a section on the lines 3—3 Fig. 1.

Fig. 4 is a section on the line 4—4 Fig. 2, the bolt 5 being shown in elevation.

Fig. 5 is a view similar to Fig. 1 showing the position of parts just before the bolt reaches its forward operative position and illustrating the manner in which the telescope sight is locked in its operative position.

Fig. 6 is a view of the telescope sight mounting with the telescope holder portion in its open position.

Fig. 7 is a section on the line 7—7 Fig. 2.

Fig. 8 is a top plan view of the bolt.

In the drawings 1 shows a breech loading shoulder arm of the well-known "Winchester" type said shoulder arm having the usual stock 2, barrel 3, receiver 4 having a top opening for the ejection of the fired cartridge shells, and the reciprocating bolt 5.

In this type of breech loading gun, the bolt is given its reciprocating movement by means of a lever member 6 which is wingable from the closed position shown in Fig. 1 to the open position shown in Fig. 2.

7 indicates a telescope sight which may have any suitable or usual construction.

2

The means for mounting the sight on the fire arm comprises a supporting bracket member 8 which is adapted to be secured to one side of the receiver 4 by means of suitable screws 9, and a telescope holding member 10 which is pivotally connected to the supporting bracket 8. The telescope supporting member 10 is provided with two telescope clamping members 11 which have a clamping engagement with the telescope sight 7.

10 The supporting bracket 8 is shown as having two upstanding ears 12, one at each end thereof, and the telescope holding member 10 is provided with an elongated hub portion 13 which is received between the said ears, said hub portion 15 having an axial bore which is aligned with apertures in the ears 12 to receive a pintle rod 14 by which the member 10 is pivotally connected to the bracket member 8.

15 The telescope supporting member 10 can thus 20 swing about the pintle 14 from its operative position shown in Figs. 1 and 3 in which the telescope sight is located directly over the barrel 3 and over the top opening in the receiver 4 through which the shells are ejected, to the open or inoperative position shown in Fig. 4 wherein the telescope 25 sight 7 is located at one side of both the barrel and the top opening through which the shells are ejected. When the telescope sight is in its operative position, the edge 15 of the telescope 30 supporting member 10 rests on the top of the receiver 4 as indicated in Fig. 1.

For swinging the telescope supporting member 10 from its open to its closed position and vice versa the elongated hub 13 of the telescope supporting member 10 is provided with a cam groove 16 in which operates the outer end of an arm 17 extending from the bolt 5. The groove 16 has a straight portion 18 at its forward end and another straight portion 19 at its rear end and a spiral or cam portion 20 intermediate its ends; said groove 16 has a length to accommodate the full travel of the bolt 5 and the arm or lug 17. In other words, said groove has a length which is at least as great as the distance which the bolt moves in either direction. The arm 17 is shown as located near the front end of the bolt and when the bolt is in its forward position said arm is located in the straight portion 18 of the slot 16. When the bolt is retracted the movement of the arm or lug 17 through the cam portion 20 of the slot will cause the telescope supporting member 10 to turn positively about its pivotal support into its open position shown in Fig. 4, in which position the telescope supporting member 10 and the telescope are 55 at one side of the open top of the receiver. Since

the arm or lug 17 is continuously confined within the groove 16, said groove and arm serve not only to give the telescope-supporting member 10 a positive turning movement in each direction, but it also serves to hold the supporting member 10 in raised or inoperative position, when the bolt is in its retracted position.

This turning or swinging movement of the telescope sight from its operative to its inoperative position occurs during the time that the end of the arm or lug 17 is moving through the cam or spiral portion 20 of the slot 16, and hence before the bolt has completed its backward movement. During the final backward movement of the bolt, the arm or lug 17 travels in the straight portion 19 of the slot 16 and thereby retains the telescope supporting member 10 in its open or inoperative position.

When the bolt is moved forwardly, the arm or lug 17 travels first through the straight portion 19 of the slot and then through the spiral or cam portion 20, during which the telescope supporting member 10 with the telescope sight is swung back into its operative position from its open position, and during the final forward movement of the bolt 5, the arm or lug 17 travels in the straight portion 18 of the slot.

Since the slot 16 is a closed slot, the position of the telescope supporting member 10 is positively controlled at all times by the engagement of the arm 17 in the slot and the swinging movement of the telescope supporting member 10 in both directions is a positive movement.

Means are provided in addition to the engagement of the arm or lug 17 in the portion 18 of the slot for locking telescope supporting member 10 in its operative position when the bolt is in its forward position.

For this purpose the bolt is provided with a locking ear 20 adapted to enter a groove 21 with which the telescope supporting member 10 is provided during the final forward movement of the bolt and while the arm or lug 17 is traveling in the straight portion 18 of the slot 16.

It will be understood that the telescope supporting member 10 will have completed its swinging movement from open position shown in Fig. 4 to closed position shown in Fig. 3 during the time that the arm or lug 17 is passing through the spiral or cam portion 20 of the slot 16. By the time that the lug 17 has passed through the spiral portion 20 of the slot 16 and has entered the straight portion 18 of the slot, the locking ear 20 has been brought into a position where it is just about ready to enter the groove 21 as shown in Fig. 5. During the final forward movement of the bolt, the locking ear 20 enters the groove 21 and thus locks the telescope supporting member 10 firmly in its operative position.

The telescope supporting member 10 is shaped to present two end portions 23 each of which has a groove 21 thereon, and I propose to provide the bolt 5 with two locking ears 20 one of which enters the groove 21 in one end portion 23 and the other of which enters the groove 21 in the other end portion 23.

The arm or lug 17 and the locking ears 20 may be made integral with the bolt or these elements may be formed on a plate or attachment 24, which is rigidly secured to the top of the bolt in some suitable way as by means of screws 25 as shown in Fig. 8.

I have provided herein means whereby the pintle 14 can be readily removed whenever it is desired to remove the telescope sight and its sup-

porting member 10 from the fire arm. For this purpose I have provided the pintle 14 with a groove 26 adapted to receive a spring retaining element 27 which is secured to the supporting bracket 8. The resiliency of the spring member 27 normally holds it in the groove 26 and thus locks the pintle in position. When it is desired to remove the telescope sight and its supporting member 10 the spring element 27 may be moved laterally to disengage it from the groove 26 thus freeing the pintle pin so that it can be readily removed. The ear 12 of the supporting bracket 8 with which the spring member 27 is associated is provided with a slot to allow the disengaging movement of said spring.

The means for securing the telescope sight to its holding member 10 may be such as to provide for lateral adjustment of the telescope. As herein shown, the rear clamping member 11 is connected to the holding member 10 by means of a single centrally located screw 28 and the front clamping member 11 as connected by a screw 29 to a disk 30 which is located in a recess formed in the under side of the holding member 10, said screw having an eccentric relation to the disk 30 so that when the screw is loosened, the disk may be turned thereby to shift the clamping member 11 laterally. This provides means for readily making lateral adjustment of the telescope sight, and by connecting the rear clamping member to the holding member by the eccentric disk means such as illustrated for the front clamping member a very fine lateral adjustment may be made.

I claim:

35. 1. A top ejecting breech loading fire arm having a barrel, a receiver open at the top for the ejection of empty shells, a reciprocating bolt, a telescope holding member having means to support a telescope sight and provided with an elongated hub portion, means pivotally connecting said hub portion to the receiver to turn about an axis parallel to the barrel, said hub portion having a cam groove which has a length no less than the distance the bolt travels in either direction, and a finger carried by the bolt and confined and operating in said groove whereby movement of the bolt in either direction operates through said finger and groove to turn the telescope holding member positively about its axis.
50. 2. A top ejecting breech loading fire arm having a barrel, a receiver open at the top for the ejection of empty shells, a reciprocating bolt, a telescope holding member having means to support a telescope sight and provided with an elongated hub portion, means pivotally connecting said hub portion to the receiver to turn about an axis parallel to the barrel, said hub portion having a cam groove extending longitudinally thereof and provided with a straight portion at each end and an intermediate cam portion, said groove having a length at least as long as the distance the bolt travels in either direction, and an arm carried by the bolt and operating in said groove whereby movement of the arm in either direction through the cam portion of the slot operates to turn the telescope holding member positively about its axis.
65. 3. A top ejecting breech loading fire arm having a barrel, a receiver open at the top for the ejection of empty shells, a reciprocating bolt, a telescope holding member having means to support a telescope sight and provided with an elongated hub portion, means pivotally connecting said hub portion to the receiver to turn about an axis parallel to the barrel, said hub portion

having a cam groove extending longitudinally thereof and which has a length at least as great as the traveling movement of the bolt, the forward end of which groove is straight and parallel to said axis, an arm carried by the bolt and continuously confined and operating in said groove whereby movement of the bolt in one direction positively turns the hub and swings the telescope-holding member from operative to inoperative position and movement of the bolt in the other direction positively turns the hub and swings the telescope-holding member from inoperative to operative position, said telescope-holding member having a groove and the bolt having a locking lug adapted to enter said groove while the arm is moving in the straight portion

of the slot thereby to assist in locking said holding member in its operative position.
